COTTON PICKING SPINDLE

Norman G. Hayward, Rte. 2, P.O. Box 1196,
Manassas, Va. 22110

Filed Aug. 12, 1970, Ser. No. 24,436

Term of patent 14 years

Int. Cl. D8—01; D15—03

U.S. Cl. D40—1

FIG. 1

FIG. 2

FIG. 3

FIG. 4

FIG. 5

FIG. 6

FIG. 7

FIG. 1 is a side elevational view of a cotton picking spindle showing my new design;

FIG. 2 is a view similar to FIG. 1 with the spindle rotated to illustrate another side thereof;

FIG. 3 is a top plan view;

FIG. 4 is a bottom plan view;

FIG. 5 is a side elevational view of a modified form of my new design;

FIG. 6 is another view of said modification from a side thereof; and

FIG. 7 is a top plan view of said modification.

I claim:

The ornamental design for a cotton picking spindle, substantially as shown and described.
